SLIDE FASTENER

Philip Reiss, Brooklyn, N. Y.

Application April 3, 1935, Serial No. 14,418

1 Claim. (Cl. 24—205)

This invention relates to new and useful improvements in garment closures, and more particularly it pertains to garment closures of the type commonly known as, "slide fasteners."

5 Slide fasteners as generally constructed comprise two stringers, each of which has a plurality of elements which, when the closure is closed, are adapted for interlocking engagement with each other. The elements are interlocked by a 10 traveler which, when moved in one direction, effects interlocking of the elements, and when moved in the other direction, releases the interlocking engagement of the elements to open the closure.

15 In certain fasteners of the above mentioned type, the two stringers are capable of complete detachment with relation to each other when the interlocking elements of the stringers are disengaged. This type of fastener is used particularly with garments such as coats and the like, in which 20 it is desired to completely open the garment.

In the last mentioned type of fastener, difficulty is often experienced in the proper positioning of the stringers with relation to each other and with 25 relation to the traveler when the closure is in its open position, and it is to this type of fastener that the present invention relates.

It is one object of the invention to provide means whereby the detachable stringer of a slide 30 fastener of the detachable type may be readily manipulated to properly position the same relative to the other stringer and the traveler.

Other objects of the invention will become apparent as the nature thereof is better understood, for which purpose reference will be had to the accompanying drawing, in which:

Figure 1 is a fragmentary view of a garment showing a fastener constructed in accordance with the present invention attached thereto,

40 Figure 2 is a fragmentary view of one of the stringers of the fastener.

Figure 3 is a sectional view taken substantially on the line 3—3 of Figure 2,

Figure 4 is a detail perspective view, and

45 Figure 5 is a detail perspective view of a slightly modified form of the invention.

Referring to the drawing by reference character, A and B designate two stringers which may be of any desired form or type, and C designates the traveler. The stringers A and B are provided at their lower ends with members 10 and 11, respectively, the member 10 being of conventional construction.

In carrying out the present invention, I provide

a manipulating member 12 which, in Figures 1 to 4, inclusive, of the drawing, is pivotally carried by the member 11. As will be noted, the member 11 has an extension 13 and the manipulating member 12 is pivotally mounted upon this extension preferably by forming an eye 14 thereon, in which the member 12 may be pivotally mounted.

By this construction and arrangement of parts, it will be apparent that the member 12 provides means for grasping the detachable stringer member B and positioning it properly with respect to the stringer A and to the traveler C in order that the traveler C may pick up the stringer B to interlock its elements with those of the stringer A 15 and effect a closing of the closure.

In that form of the invention illustrated in Figure 5, the member 11 is provided with an integral extension 16 which is rigid with relation to the member 11. In this form of the invention 20 the manipulating member is provided by the extension 16 which will be of sufficient size to render the same operable in the manner described for the manipulating member 12.

From the foregoing it will be apparent that the 25 present invention provides a new and improved means which will greatly facilitate the proper positioning of the detachable stringer member with respect to the traveler and the associate stringer member in fasteners of this type.

While the invention has been illustrated in its 30 preferred forms, it is to be understood that it is not to be limited to the specific construction shown and that it may be carried out in other forms without departing from the spirit thereof.

Having thus described the invention, what is 35 claimed as new, is:

In a fastener of the type described including a pair of interlocking stringers adapted to be entirely separated from each other, and a traveler 40 for connecting and disconnecting said stringers, a manipulating member secured to one of said stringers, said manipulating member comprising in combination, a main body portion for receiving and embracing the end of one of said stringers, 45 an extension projecting at right angles from the main body portion of the manipulating member, said extension lying wholly beyond the end of the stringer to which it is attached, an eye member carried by said extension, and a manipulating 50 element pivotally mounted in said eye member and depending therefrom beyond the end of the extension.

PHILIP REISS.
